UNITED STATES PATENT OFFICE.

LAURITS DINESEN, OF MINNEAPOLIS, MINNESOTA.

TEAT CUP.

Application filed November 27, 1925. Serial No. 71,631.

My invention provides an improved teat cup for use in connection with milking machines and, generally stated, it consists of the novel construction, combinations and arrangement of parts hereinafter described and defined in the claims. Particularly this invention relates to teat cups of the type generally designated as two-chambered teat cups. Teat cups of this type usually comprise a thin metal outer shell and a flexible inner wall of rubber, the said two chambers being provided with connections whereby they may be alternately subjected to suction or partial vacuum, thereby alternately expanding and contracting the elastic inner wall.

My invention has for its object to simplify the construction and greatly improve the action of these two-chambered teat cups. Several forms of the improved teat cup are illustrated in the accompanying drawings wherein like characters indicate like parts throughout the several views.

Referring to the drawings:

Fig. 1 is a plan view of the improved teat cup;

Fig. 2 is an axial section of the teat cup, showing the elastic inner tube applied in the metallic outer shell but not stretched to final position;

Fig. 3 is a view corresponding to Fig. 2, but showing the elastic inner tube stretched to final position;

Fig. 4 is a plan view of the elastic inner tube removed from the metallic shell;

Fig. 5 is a section on the line 5—5 of Fig. 4;

Fig. 6 is an axial section illustrating a slightly modified form of the elastic inner tube; and

Fig. 7 is a plan view illustrating a still further slightly modified form of the elastic tube.

What is at present believed to be the preferred form of the teat cup is illustrated in Figs. 1 to 5, inclusive. The metallic outer shell 8 is preferably made from a thin metal tube, which, at one end, has a slightly outwarded joint flange 9 and at its other end is contracted onto a grooved bushing 10, which latter, though a minor feature, has an important purpose that will presently appear. Extended longitudinally of and secured to the exterior of the shell 8 is a small nipple-forming metal tube 11 that is connected to the interior of the casing quite close to the teat-receiving end thereof by an air port 12.

A rubber inner wall-forming tube 13 is

formed at its teat-receiving end with a diametrically enlarged portion 14 having an in-turned annular flange or diaphragm 15. On its exterior, adjacent to or extending from its enlarged end 14, said tube is provided with an integral backwardly and inwardly turned elastic joint flange 16 that is adapted to engage over the end flange 9 of the shell 8 and to form an air-tight joint therewith. On its exterior, the tube 13 is formed with spiral ribs or enlargements 17 that preferably do not normally contact with the interior of the shell but are adapted to be expanded into contact therewith when partial vacuum is produced within the outer chamber formed between the shell and flexible tube. At its inner end, the rubber tube 13 is formed with an integral tubular stem 18 that extends outward through the axial opening, which, as shown, is afforded by the bushing 10. The stem 18, near its base, is of slightly greater diameter than the smallest diameter of the corrugated bushing 10. The entire inner or rubber tube 13, its flanges and extensions, are of quite soft and very elastic rubber, so that the large portion of the tubular stem 18 may be quite readily pulled through the bushing. Fig. 2 shows the rubber inner tube applied but not stretched, and Fig. 3 illustrates the condition thereof when pulled to its limit through the bushing, and by reference to said Fig. 3, it will be noted that the several corrugations of the bushing are tightly imbedded in the base of the tubular stem 18, so as to form an air-tight joint and to hold the inner tube longitudinally stretched substantially to the extent shown in Fig. 3.

When the teat cup is applied, the teat will, of course, be placed within the tube 13 and the elastic flange or annular diaphragm 15 will be forced upward against the cow's udder. The teat will thus be very closely seated in the teat cup without any harsh application, pinching action or hard rubbing engagement. It should be here further noted that the enlarged head end of the rubber inner tube projects very considerably beyond the metallic outer shell, and as the same is quite flexible, and elastic, it will, under the pulsating actions produced in the milking, be caused to expand and contract or partially collapse and extend itself to adapt itself to the base of the teat and the cow's udder, thereby producing an action quite similar to that produced in milking.

When the teat cup is applied to the milking apparatus, the tubular stem 18 will, of course,

be connected to the milk-conducting tube, the nipple end of the tube 11 will be connected to a pulsator or means for alternately connecting the outer chamber of the teat cup 3 to partial vacuum and to the atmosphere; and through the pulsator, already in use and the action of which is well known, the suction and relief actions in the two chambers of the teat cups will be alternated, or the inner chamber may be under constant vacuum. When the tube 11 and outer chamber of the teat cup are subjected to partial vacuum, the flexible inner tube 13 will be expanded so that the teat will be relieved from pressure and 10 will be free to expand. Then, when the tube 18 and the inner chamber of the teat cup are subjected to partial vacuum while the tube 11 and the outer chamber of the teat cup are subject to atmospheric pressure, the rubber inner tube will be contracted onto the teat and the milk will be squeezed therefrom and caused to flow downward and outward through the stem 18 and milk tube, not shown. The spiral ribs or enlargements 17 15 on the inner tube cause the same to progressively expand and contract on a spiral line. When the outer air chamber is open to the atmosphere, the suction produced or maintained within the inner or teat cup chamber 20 will cause or permit the flexible tube to contract, and as the contraction will be greater in the spiral space between the spiral rib or ribs, the teat will be squeezed with a spirally applied pressure having a downward trend, 25 and this produces a milking action very closely approximating that produced by the fingers in a hand operation of milking.

The teat cup described, in practice, has been found to be very highly efficient for the 40 purposes had in view. It is also very sanitary, inasmuch as it may be very easily taken apart, cleaned and reassembled. It has a minimum number of parts and no parts that are adapted to be easily broken.

45 The flexible inner tube shown in Fig. 6 is like that shown in the views described, except that the spiral ribs or enlargements 17 at the interior of the tube are hollowed out at 17^a so that the tube is not thicker at the side ribs or enlargements than at intervening portions. In the forms of the inner tube already described, the ribs 17 are in multiple spiral arrangement. In Fig. 7, however, is 50 illustrated a tube in which a single spiral rib 17^b is applied on the exterior of the tube 13, this spiral being given very much less pitch than the spiral ribs 17 before described. In the forms of the teat cup inner tube illustrated in Figs. 1 to 6, inclusive, the spiral ribs 55 or enlargements are of the same material as the body of said tube, to wit: of flexible rubber; but in the form shown in Fig. 7 the rib 17^b is a separately formed element made of canvas or the like, cemented or otherwise secured to exterior of the elastic body of the 60

inner tube. The rib 17^b will not be capable of much expansion or contraction although it may be quite readily buckled or collapsed, but the rubber body between the rib will be very elastic and capable of free expansion and 70 contraction and of longitudinal extension.

By applying the rubber inner tube within the shell under normal axial stretch and tension, the elasticity thereof is increased. The outer shell, as is evident, will limit the expansion of the spirally enlarged inner tube and the spiral enlargements will prevent this expansion from cutting off communication between the extreme ends of the shell. The best 75 results are attained by giving the spiral enlargement of the inner tube increased thickness so that the intervening portions of said tube will be much more flexible than the said spiral enlargement. These features combine 80 to give a downward pull on the teat that will 85 closely approximate the action produced by the hand in the milking operation.

It is evident that when the spiral surface of the elastic inner tube is radially expanded, 90 the said spiral surface will tend to shorten up and decrease the space between the spirals, and this would have a tendency to pinch the teat. However, with the spiral surface held against movement at both ends, this endwise contraction and closing of the spirals is prevented. This, combined with the outer shell arranged to limit the radial expansion of the 95 spiral surface, produces a highly efficient and the most desirable kind of milking action.

100 What I claim is:

1. A teat cup for milking apparatus comprising a rigid tubular outer shell and a flexible resilient teat-receiving inner tube, said shell and tube being connected with air-tight joints at the ends of said shell, and the wall of said tube being spirally enlarged between its ends, whereby said shell limits the expansion of the spirally enlarged surface of said tube and the air-tight joints at the ends thereof serve to hold said spiral surface against endwise contraction under radial expansion. 110

2. A teat cup for milking apparatus comprising a rigid tubular outer shell and a flexible resilient teat-receiving inner tube, said shell and tube being connected with air-tight joints at the ends of said shell, the wall of said tube being spirally enlarged between its ends, whereby said shell limits the expansion of the spirally enlarged surface of said tube and the air-tight joints at the ends thereof serve to hold said spiral surface against endwise contraction under radial expansion, and said tube being formed with an enlarged flexible teat-receiving end terminating in an inturned annular web and further provided with a backwardly and inwardly turned external flange overlapping the adjacent end of said outer shell. 115 120 125

3. A teat cup inflation, comprising a flexible teat-receiving tube having an enlarged 130

annular teat-receiving end, an annular air sealing flange depending from said enlarged end, and a reduced tubular end having an air sealing portion adjacent the lower end of said inflation, the wall of said inflation being spirally enlarged between said ends.

4. A teat cup inflation, comprising a teat-

receiving tube having portions adjacent its upper and lower ends for air tight engagement with a teat cup shell, the exterior wall of said inflation being spirally enlarged between said ends. ¹⁰

In testimony whereof I affix my signature.

LAURITS DINESEN.
